BAND-SAWING MACHINE.

Application filed June 11, 1926. Serial No. 115,173.

This invention relates to improvements in band-sawing machines, and more particularly to the mounting of the driving motor thereof.

In band sawing machines of the type comprising a pair of wheels rotatably mounted on parallel shafts, and an endless saw trained about these wheels, the practice heretofore has been to fix the driving electric motor directly to the base of the machine and to connect the same to the lower shaft by means of a suitable coupling. When it is found necessary to realign the lower wheel-supporting shaft for any reason in this prior construction, realignment of the driving motor and the associated parts is also necessitated to maintain smooth running of the driving mechanism as well as to maintain the uniform air gap between the rotor and stator of the motor. The amount of power required for efficient operation of these machines is relatively large, the driving motor and its associated parts being therefore correspondingly large and cumbersome. This realignment of the driving motor, as well as installation of the same in the first instance, is for this reason effected with a certain amount of difficulty and inconvenience.

One of the objects of the present invention, therefore, is to provide an improved band sawing machine in which the driving motor is mounted directly upon the lower driving shaft so that the motor armature shaft is in effect a continuation of the lower wheel shaft the rotor of the motor being fixed upon this shaft and the stator being held against rotation with the latter and journaled on the same in fixed relation with respect to the rotor whereby a uniform air gap between the motor parts is maintained at all times regardless of the manner of adjustment of the lower wheel shaft.

Another object is to provide an improved band sawing machine of the character described wherein the driving means therefor may be placed in operating position or removed therefrom with greater ease and with a greater degree of accuracy than is possible in machines of this type constructed heretofore.

Other objects and advantages will herein after appear.

For the purpose of illustrating the invention, one embodiment thereof is shown in the drawings, in which:

Fig. 1 is a side elevational view of the improved machine, partly broken away and partly in section;

Fig. 2 is a front elevational view, partly broken away, looking toward the right in Fig. 1;

Fig. 3 is an enlarged sectional view, taken on the line 3—3 of Fig. 1; and

Fig. 4 is a section on line 4—4 of Fig. 3.

In Figs. 1 and 2 is shown a band sawing machine of the usual type comprising a suitable frame designated generally by the reference numeral 10 and provided with a base 11, upper and lower wheels 12 and 13, parallel shafts 14 and 15 supporting these wheels, shaft 15 being the driving shaft to which wheel 13 is fixed, and the usual endless band saw 16 arranged about wheels 12 and 13.

To provide for realignment of shaft 15 the ends thereof may be supported in suitable journal boxes 17 and 18 each adjustable horizontally and vertically. These journal boxes will be briefly described although no claim is herein made for them per se.

As more clearly shown in Figs. 3 and 4, each journal box is provided in its upper end with a T-slot 18 into which loosely fits a T-head 19 formed at the lower end of a hanger 20, the latter being provided with a depending lug 21 having a threaded opening into which one end of an adjusting bolt 22 is screwed, the latter extending loosely through the upper portion of the journal box, as shown, and suitable collars 23 and 24 being fixed on the bolt at either side of the box for preventing relative movement of the latter axially of the bolt. From the foregoing it will be seen that by placing a suitable wrench over the end 25 of bolt 22, the latter may be rotated to effect horizontal adjustment of the journal box with respect to its hanger 20.

For the purpose of supporting hanger 20 for vertical adjustment with respect to the frame 10 of the mill, a suitable base 26 is secured to the underside of base 11 by means of bolts 27. Hanger 20 is provided with a vertically arranged portion 28 directed to

ward shaft 14 and threaded at its end, the latter receiving an adjusting nut 29 seating upon base 26, as shown. A suitable washer 30 may be interposed between base 26 and nut 29. It will thus be seen that nut 29 provides the means whereby hanger 20 is supported by base 26, and that upon the turning of nut 29 hanger 20 and the journal box carried thereby may be adjusted vertically.

10 The tension in the saw 16 exerting an upward pull on shaft 15 and wheel 13 carried thereby tends to lift said shaft, the journal boxes and their hangers 20 upwardly, this in turn tending to lift nuts 29 from their seats on base 26. To provide against this, bolts 31 and 32 are interposed between each hanger 20 and its base 26 and are threaded into the latter for vertical adjustment with respect thereto, the heads of these bolts engaging the 15 adjacent upper end of hanger 20, as shown. The bolts 31 and 32 are normally in tight engagement with the adjacent upper end of corresponding hanger 20, and nut 29 normally seated tightly upon base 26, these parts 20 thus cooperating with each other to maintain the vertical adjustment of hangers 20 with respect to their respective bases 26. Assuming that it is desired to raise one of the journal boxes a certain amount, bolts 31 and 25 32 thereof are each screwed further into base 26 until their respective heads are spaced this same amount from the upper end of the hanger. Nut 29 is then tightened upon the upper threaded end of portion 28 to raise 30 the hanger until the upper end thereof is again in tight engagement with the respective heads of bolts 31 and 32. If it is desired to lower one of the journal boxes, nut 29 is unscrewed the desired amount from the threaded end of portion 28 and bolts 31 and 32 then unscrewed from base 26 until their 35 respective heads come into tight engagement with the upper end of the hanger.

Thus in each hanger bolts 31 and 32 act 40 to lock nut 29 in its adjusted position, while the latter in turn acts to lock bolts 31 and 32 in their respective adjusted positions.

From the foregoing it will be seen that means have been provided for supporting the 45 journal boxes for both horizontal and vertical adjustment, the horizontal adjustment being made by turning bolts 22 and the vertical adjustment being made by manipulating either or both sets of nuts 29 and bolts 31 and 32 in the manner explained.

For the purpose of driving shaft 15, it is contemplated according to the present invention to mount an electric motor 33 directly on said shaft for bodily movement there- 50 with upon adjustment or movement of the same by means of the adjustable journal boxes 17 and 18, or by any other means or for any other purpose. The rotor 34 of the motor is fixed on shaft 15, and the motor cas-

ing 35 with the stator 36 attached is journaled on this shaft by means of suitable bearings 37, bearings 37 thus holding stator 36 in concentric relation with respect to rotor 34 at all times, maintaining a uniform air gap between these parts regardless of adjustments of shaft 15, while at the same time permitting free rotation of said shaft and rotor 34 with respect to stator 36 and the motor casing 35 supporting the latter. Lugs 38, which may be formed integrally with 55 motor casing 35, coact with the underside of base 11 to prevent rotation of the stator with the shaft upon operation of the latter, a certain amount of loose play being provided between 11 and the lugs 38, as more clearly 60 shown in Figs. 1 and 2, to permit of such free lateral bodily movement of the motor with shaft 15 as is ever necessary for purposes of adjustment, while holding the motor casing and stator 36 against rotation with rotor 34 65 and the shaft 15. As will be observed, lugs 38 offer no interference or obstruction to bodily movement of the shaft and motor longitudinally in either direction.

By means of this construction, perfect 70 alignment for all positions of adjustment of shaft 15 is maintained between the same and the armature shaft, since the latter is but a continuation of shaft 15. This construction, furthermore, provides for a constant and uniform air gap between rotor 34 and stator 36 75 for all positions of adjustment of shaft 15 since the motor casing 35 and the stator 36 carried thereby are so mounted on shaft 15 as to be bodily movable with the latter while 80 being held against rotation with the same. This improved manner of mounting the driving motor directly on the lower wheel-supporting shaft also facilitates placement of 85 the same into operating position as well as removal of the motor for repair or other 90 purposes, and provides for a greater degree of accuracy not possible heretofore as regards 95 a uniform air gap between the rotor and stator. 100

110 Although the improved manner of mounting the driving motor and the construction whereby this is possible has been shown and described in connection with the driving shaft 15 and adjustable bearings 17 and 18 115 therefor, it will be understood of course that in some cases these bearings may be of the non-adjustable type, alignment of the saw being effected and maintained in some other manner. It will be appreciated, furthermore, that while the improved construction has been shown embodied in a band mill, the invention is of much broader adaptation and may be used in other connections and in 120 machines of other types as well.

125 While one embodiment of the invention has been shown and described, of course various changes may be made in the size, shape and

arrangement of the parts without departing from the spirit of the invention or the scope of the claims.

The invention claimed is:

- 5 1. A band saw comprising a drive shaft, a band wheel fixed to said shaft, an electric motor mounted directly on and supported by said drive shaft in spaced relation to the band wheel, the rotor of said motor being fixed to said shaft for rotation therewith, the stator of said motor being loosely mounted on said shaft, means for preventing rotation of the stator, and means independent of the motor for supporting said drive shaft.
- 10 2. A band saw comprising a frame, a drive shaft, means for supporting the drive shaft for vertical and horizontal adjustment, a band wheel fixed to said drive shaft, an electric motor mounted directly on and supported by said drive shaft, the rotor of said motor being fixed to said shaft for rotation therewith, the stator of said motor being loosely mounted on said shaft, and interfitting means on the stator and frame for preventing rotation of the stator while permitting it to move horizontally and vertically as and when the shaft is adjusted.
- 15 3. A band saw comprising a frame, an upper band wheel supported for rotation about a fixed axis on said frame, a lower band wheel alined with the upper band wheel, a drive shaft on which the lower band wheel is fixed, adjustable journal boxes for the drive shaft providing for alinement of the band wheels, an electric motor mounted directly on and supported by the drive shaft and having a rotor fixed to the shaft for rotation therewith and a stator loosely mounted on the drive shaft, and cooperating means between the
- 20 stator and the frame for preventing rotation of the stator while permitting it to move as and when the journal boxes for the drive shaft are adjusted.
- 25 4. In a band mill of the character described, the combination with the wheel-supporting and driving shaft thereof, of an electric motor having the rotor thereof fixed on said shaft and its stator journaled on the same, adjustable means supporting the ends of said shaft for rotation about a fixed axis in any adjustment, and means holding said stator against rotation with said shaft while permitting bodily movement of said stator with the latter upon adjustment of the same by said adjustable means whereby a constant and uniform air gap between said motor parts is maintained for the various positions of adjustment of said shaft.
- 30 5. In a band mill, upper and lower wheels, a saw arranged thereabout, a supporting and driving shaft for one of said wheels, adjustable bearings supporting the shaft adjacent its ends for rotation about a fixed axis in any adjustment, a motor of the rotary type mounted on and supported by said shaft for bodily movement therewith upon adjustment of the same by said bearings, the rotary element of said motor being fixed to said shaft, and means holding the remaining parts of said motor against rotation with said shaft and said motor element fixed thereto while permitting said bodily movement of said motor.
- 35 6. In witness whereof, we hereto affix our signatures.

ROSS E. LANGILL.
WILLIAM B. GRUETER.
